UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

RAILWAY CAR.

Application filed June 27, 1927. Serial No. 201,877.

My invention relates to improvements in railway cars, especially to that type of car commonly known as a plow car, such a car being more particularly identified as a car having a horizontal floor, vertically suspended pivoted side doors and side stakes intermediate the side doors, said stakes being usually provided with rub plates to guide the unloading plow during its passage through the car.

10 In cars of the identified type it has been customary to space the side rub plates on opposite sides of the car approximately 8'-8" apart and a large number of cars are now in service with this spacing and therefore the 15 unloading plows have been largely standardized for use with this spacing. The primary service for which such cars are built has been for side filling of railway tracks, trestles and the like rather than as revenue 20 producing cars.

A purpose of my improved construction is to increase the cubic capacity of such cars to an extent which will justify their use in revenue freight service, obtain greater 25 strength and efficiency in the car parts, especially those parts which are affected by the passage of a plow through the car body and still retain the standardized width of 8'-8" between plow guides.

30 Broadly stated, my invention resides in the arrangement of and relationship between the plow guides, car stakes, car doors and car floor whereby these members are arranged to provide a car of standard width throughout 35 the length of the car in the plane of the plow guides, the car stakes and car doors being deflected outwardly above the plow guides to obtain increased carrying capacity within the car body.

40 Other objects and advantages of my invention will more fully appear from the drawings, description and claims appended hereto.

In the drawings, forming a part of this 45 specification, Fig. 1 is a side elevational view of a portion of a car embodying my improved construction. Fig. 2 is a perspective view of the corner stake construction. Fig. 3 is a transverse sectional view taken through the 50 car, said section being taken about midway of the length of the car. And Fig. 4 is a vertical longitudinal sectional view taken substantially on the longitudinal center of the car.

In said drawings, my improved construc-

tion is shown as applied to a car of the convertible type adapted to form either a level floor gondola or a center discharge V-shaped hopper car, concentrated in length to discharge between the trucks. In said drawing 55 1-1 indicates the centersills of the car; 2-2 the longitudinal intermediate sills; 3-3 the longitudinal side sills, said intermediate sills 2 and side sills 3 being suitably spaced apart by fillers 4. The intermediate sills 2-2 are 60 tied together by channels 5, the latter being 65 braced to the intermediate sills by gussets as indicated at 6-6. Part of the usual bolster construction identified with this type of car is shown at 7 and the end sill is indicated at 8. A longitudinal hopper is disposed between 70 75 the intermediate sills 2-2, said hopper including fixed, longitudinally extending sloping sections as indicated at 9 and 10 and a longitudinally extending pivoted dumping door at 11. On each side of the V-shaped hopper section, the level floor of the car is composed of longitudinal fixed sections, preferably formed of lumber as indicated at 12-12 and, at each end of the car above the trucks, the floor is composed of fixed floor sections 13. 80 The body or upper portion of the car, broadly, includes a supporting framework A, swinging side doors B, and movable end gates C. 85 The supporting framework A is composed of corner stakes 14, intermediate stakes 15 and top rail member 17. Each corner stake 14 is purposely made wide and preferably consists of two vertical pressings or shapes 90 united by a sheet as will be evident from Figures 2 and 4. The stakes 14 and 15 are secured to the side sills and each extends vertically above the floor for an appreciable distance as indicated at 18 and thence flare outwardly and upwardly as indicated at 19, 95 thence upwardly as indicated at 20, thence inwardly and upwardly as indicated at 21, thus presenting a recessed or offset portion intermediate the vertical section 18 and the top rail member 17. The vertical sections 18 of 100 the stake adjacent the floor are fitted with wear plates 118 and 218 against which the unloading plow is adapted to bear during its passage through the car and thus the lower portions of the stakes constitute plow guides. 105 It will be noted that the stakes are thus deep of section adjacent the plow guides, thereby providing for strength to withstand the side

strains incidental to the plow. Each top rail member 17 preferably consists of a Z-bar applied as shown and extends from end to end of the car. A wooden filler member 23 is disposed in the angle of the Z-bar and is chamfered as indicated at 24 for load shedding purposes and cut away at the end of the car as indicated at 124 for the purpose of safety appliances.

10 The side doors 3 are each formed of a series of wooden planks 25 suitably tied together by a framework including vertical hinge members 26 and horizontally extending marginal member 27. The hinge members are fitted at their upper ends with hinge straps 28 by which the doors are suspended from hinge butts 29, the latter being rigidly secured to the top rail member 17, in the corner pocket provided by the Z-bar 17. At their 15 lower end two hinges per door are fitted with extensions 30 with which an operating shaft 31 is adapted to co-operate for the purpose of maintaining the doors in closed position, said operating shaft 31 being movable in slots 32 formed in the stakes 15 and in the inner vertical members of the end stakes 14. The doors are preferably operated in groups each consisting of a plurality of doors from a corner of the car where the shafts are fitted with 20 handles 33. The side door hinges 26 are bent inwardly at their upper ends as indicated at 34 and adjacent the plow guides as indicated at 35 and 36 for the purpose of conforming to the shape of the doors. The bend at 34 is for 25 the purpose of disposing the pivotal center of the door inwardly of the main body thereof, thereby permitting the door to swing to closed position by its own weight. The bends 35 and 36 are for the purpose of disposing 30 sloping sections in the doors whereby the lading intermediate the widened portion of the sidewalls will be directed to the narrowest portion of the car, it being observed that the inclined planks of the door are so arranged as 35 to shed the load over the top edges of the 40 guide plates 118 and 218.

The section of floor above the center hopper is formed of two convertible sections 37-37 adapted to form in one position the level floor 45 of a car as indicated in full lines in Fig. 3 and movable outwardly and upwardly to form the sloping walls of a center discharge hopper, as indicated in dotted lines in Fig. 3. In the latter position the convertible sections 37 rest 50 against the side stakes and grooves are provided in the planks as indicated at 38 within which the ends of the convertible floor sections rest, the side doors at this point being provided with a somewhat heavier plank 39 which fills the space intermediate the side 55 doors and convertible floor section.

The side stakes of the car are shaped to conform to the shape of the doors and at each side of the door (see Fig. 1) there are abutting flanges 40 extending outwardly from the

adjacent stake to overlap the edges of the adjacent door for a limited distance, thereby securing tight joints. When the convertible sections 37-37 are disposed as a portion of the floor, the car then presents a car having a substantially level floor from end to end and from plow guide to plow guide.

The end gate C consists of a plurality of planks 41 united by a series of posts 42, the latter being adapted to rest in pockets 43 formed in the floor of the car. The end gates C may either be disposed as the ends of a center discharge hopper as shown in Fig. 4 or moved to the ends of the car to form the ends of a flat floor gondola. The end gate C is 75 formed of a width substantially equal to the distance between the top rail members 17, thereby providing for convenient handling and the space intermediate the end gate and the bulged out portion of the side wall is then 80 sealed by furring strips as indicated at 44 and 45. The sealing strips 44 are secured to the end stakes for co-operation with the end gate when positioned to form the end of a level 85 floor gondola car and the sealing strips 45 are disposed on the side doors to co-operate with the end gate when positioned to form the end of a concentrated hopper discharge car as indicated in Fig. 4.

I claim:

1. In a railway car, the combination with spaced plow guides on either side of the car; of a level floor extending between the plow guides; a side wall spaced outwardly beyond the plow guides; and means adapted to bridge the distance at an incline between the side walls of the car and the level floor.

2. In a railway car, the combination with a supporting framework including plow guides; of swinging side doors forming walls offset outwardly from said plow guides; and means associated with the doors adapted to direct the lading away from the spaced side walls towards the plow guides.

3. In a railway car, the combination with a level floor; of vertical plow guides extending above said level floor; side walls offset outwardly beyond said plow guides; and means extending between the plow guides and the said walls of the car for the purpose of bridging at an incline, the space between the plow guides and the side walls of the car.

4. In a railway car, the combination with side stakes having plow guides; of a top rail member in substantially the same plane as the plow guides; and swinging side doors pivoted intermediate said side stakes, said doors and stakes having a bulged out portion intermediate the top rail member and plow guides for the purpose of providing a car of increased 115 effective width.

5. In a railway car, the combination with permanent side stakes; of side door sections pivoted intermediate said stakes, said stakes and doors having the lower portion thereof 120

diverted inwardly and downwardly to present a car of restricted width for an appreciable distance above the floor line of the car.

6. In a railway car, the combination with 5 plow guides on either side of the car; of a substantially level floor extending between said plow guides; side walls having portions extending in substantially the same plane as the plow guides throughout the length of 10 the car, said side walls above the plow guides being offset outwardly from said plow guides to thereby provide a widened portion and inclined means associated with said side walls adapted to divert lading from said 15 widened portion of the car to the narrower portion of same.

7. In a railway car adapted to have a plow passed therethrough, the combination with side stakes having plow guides located 20 adjacent the floor line; of a top rail member substantially in vertical alignment with said plow guides; and a stake section connecting said plow guides and top rail member, said stake having an offset portion whereby the 25 car is increased in width intermediate the top rail and plow guide.

8. In a railway car, the combination with stakes having the lower portion thereof extending vertically above the floor line for an 30 appreciable distance for the purpose of presenting guides for an unloading plow, said stakes being flared outwardly and upwardly above said plow guides to present a car of increased width throughout the length thereof; of swinging side door sections pivoted 35 intermediate the stakes, said doors conforming to the shape of the stakes.

9. In a convertible railway car adapted to have portions of the floor of the car forming in one position a level floor car and in another position the sloping walls of a center discharge hopper car, the combination with side walls including permanent stakes, 40 of swinging side door sections intermediate said permanent stakes, said stakes and doors having the lower portions thereof deflected inwardly and downwardly beneath the convertible floor section when the latter is in 45 position to form a center discharge hopper 50 car.

10. In a convertible railway car, the combination with swinging side doors having walls with portions in different planes thereby presenting a car of varying width from 55 top to bottom; of an end gate adapted to be positioned in the plane of said doors, said end

gate being of a width to correspond substantially with the narrowest distance between the side walls of the car; and means on the side doors adapted to seal the space 60 intermediate the widest portion of the car and end gate.

11. In a convertible railway car, the combination with a supporting frame work including side stakes; of swinging doors pivoted intermediate the side stakes; a convertible floor adapted to form in one position a level floor car and in another position the sloping walls of a center discharge hopper car, said floor sections when positioned as 70 the sloping walls of a center discharge hopper having their outer ends resting on the inner face of the side stakes; and means on the side doors adapted to bridge the distance 75 intermediate the convertible floor sections and side doors.

12. In a convertible railway car, the combination with a supporting framework including side stakes having bulged out portions intermediate the top of the car and the 80 floor; of swinging side doors pivoted intermediate the side stakes, said doors being shaped to conform to the shape of the stakes, movable end walls adapted in one position to form the end walls of a center hopper discharge car and in another position to form the end walls of a level floor gondola car, said ends being of a width to correspond substantially to the distance between the top rails of a car; and means carried by the side 90 walls of the car to seal the space between the end walls and the bulged out portions of the side walls.

13. An interchangeable plow and revenue load-carrying car having a body portion 95 provided with a floor and side walls, the top and bottom portions of one side wall being spaced from the top and bottom portions of the other side wall a distance corresponding to the width of a standard plow, each side 100 wall including stakes and top-hung pivoted side doors, the stakes and doors being, for the major portion of their vertical height above the floor line, appreciably outwardly offset from the plane defined by the inner 105 surface of said upper and lower portions of the side wall whereby to provide increased load-carrying capacity.

In witness that I claim the foregoing I have hereunto subscribed my name this 11th day of June, 1927.

ARGYLE CAMPBELL.
